UNITED STATES PATENT OFFICE.

WILLIAM DOUGLAS SMITH, OF LUMBER BRIDGE, NORTH CAROLINA.

VARIABLE-COLOR LAMP.

Application filed January 23, 1925. Serial No. 4,274.

To all whom it may concern:

Be it known that I, WILLIAM DOUGLAS SMITH, a citizen of the United States, residing at Lumber Bridge, in the county of 5 Robeson, State of North Carolina, have invented a new and useful Variable-Color Lamp, of which the following is a specification.

An object of my invention is to provide a 10 lamp shade to cover an electric or other light with means for changing the color thru the said shade.

Another object of invention is to provide a shade for lamps with a cavity in the shade 15 for the reception of a colored liquid and means for forcing said liquid into said cavity, and means for withdrawing said liquid from the cavity.

Another object of invention is to provide 20 a lighting unit having a shade, the color of which can be varied at will, receptacles in the base of said lighting unit, and magnets for contracting said receptacles to cause the liquid to be forced into a space in a shade for 25 the lighting unit for the purpose of changing the color of the light emanating from the shade of the lighting unit.

Having thus stated some of the objects of 30 invention, a brief description of the drawings will be given.

Figure 1 is a front elevation of my lighting unit.

Figure 2 is a sectional view taken along the lines 2—2 in Figure 4.

Figure 3 is a sectional detail view showing the top of the receptacle for the colored liquid, and the manner of connecting it with the cavity between the inner and outer globes.

Figure 4 is a sectional plan view taken 40 along the lines 4—4 in Figure 2.

Figure 5 is an enlarged detail view of the top of the outer globe.

Figure 6 is a sectional plan view taken 45 along the lines 6—6 in Figure 2.

Having thus briefly described the different figures in the drawings, a more detailed description of the drawings, and the method of operation of the invention will now be given 50 in which like reference numerals represent corresponding parts thruout the drawings.

The numeral 1 represents the shell of the base portion of the lighting unit. This shell houses the operating parts of the device, and 55 has a flat bottom portion which is adapted to be secured to a support (not shown) by

any desired means such as screws. This base portion or shell has side portions which extend upward to the member 2 which covers the top of this shell. This member 60 or plate 2 has apertures therein for the purpose of mounting a source of light and also for the passage of the liquid from the containers to the globe portion, as will be explained later. 65

On top of this plate member 2 is mounted the transparent globe 3, which is preferably made of glass, the texture of the glass or other transparent substance being of such nature as to prevent the liquid hereinafter 70 described from adhering to the same. This globe 3 extends upwardly for some distance, then describes an arc of 180 degrees, then extends downwardly to the opposite side of the plate 2. The above description is for 75 the sectional view as shown in Figure 2, it being understood that the globe 3 is circular as shown by Figure 6. Upon reaching the plate 2 the globe 3 projects inwardly for some distance, then upwardly, then proceeds 80 to follow the contour of the portion 3, but a small distance therefrom, thereby leaving a cavity between the portions 3 and 5. In other words, the transparent portion consists of one globe within another globe, the 85 lower ends of the same being cut off, bent inwardly, and joined together, thus leaving a space 7 between the two portions of the globe. 90

The outer portion 3 has a perforation 90 therein at its highest point which is represented by the numeral 8. Immediately below this perforation, and resting normally upon the inner portion 5 of the globe is the circular float 9, the purpose of said float being explained later in the description. 95

It will thus be readily seen that the portions 3, 4, 5, and 6 of the globe are integral and form the complete globe of the device, with a continuous cavity between the outer 100 and inner portions of the globe.

In the center of the plate 2 there is a perforation in which is mounted a socket 10 for an electric light 11. This socket may be of the conventional design. This socket is 105 wired to a source of electric energy by means of wires 12.

Within the base 1 there are a plurality of flexible hollow bladders 13, four being 110 shown in the drawings. These bladders are for the purpose of holding the colored liquid. These bladders are mounted in an upright

position and have a neck portion 14 which extends thru a perforation in the plate 2, said perforation being reamed or broadened in diameter in the upper portion thereof. 5 The portion 4 of the globe has a perforation therein and a member 15 is mounted therein. This member 15 is hollow, has the lower end thereof enlarged and sharpened on its outer surface to fit the reamed or 10 enlarged portion of the hole in the plate 2 thru which the neck of the bladder extends.

On each side of each of the bladders there is mounted a series of electro-magnets 16. These are mounted on a bolt 17 which extends 15 from the lower portion of the base 1 thru the plate 2. Above and below each bladder is a soft iron member 18 which is also mounted slidably on the bolts 17. The upper soft iron member 18 has a perforation 20 central thereof thru which the neck of the bladder passes on its way to penetrate the perforation in the plate 2.

It might here be stated that these electro-magnets may be connected to any source of 25 direct current, or may be connected to a number of dry cells for operation. These electro-magnets are connected to a source of direct electric energy by means of the wires 19 which penetrate the member 1 at the 30 point 20.

The base portion 1 has clamps 21 connected to the upper portion thereof by means of bolts 22 which serve to hold the globe portion 5 in operative position when 35 the device is assembled for use.

The method of operation is as follows:

The parts are assembled as shown in the drawings and above described. In the present instance there are four different bladders in the base portion. Let us suppose that a red liquid is poured into one of these bladders, a yellow liquid into the second bladder, a green liquid into the third bladder, and a blue liquid into the fourth bladder. 45 The globe portion is then snapped into position and held in such position by means of the clamps 21. The necks of the bladders extend upwardly thru the perforations in the plate 2 and the beveled members 15 enlarge the upper portions of these necks, fit tightly therein, and thus the bladders are directly and separately connected to the cavity 7 between the two portions of the globe. Each of the bladders has a set of 55 electro-magnets on each side thereof. Each electro-magnet is wired separately from the electro-magnets of the other bladders. Each set of electro-magnets surrounding the different bladders has a switch for operation. 60 When a switch is pressed for the set of electro-magnets located on each side of one of the bladders the electro-magnets attract the soft iron members 18, the bladder is compressed, the liquid contained therein is 65 forced up thru the neck portion thereof

and into the cavity 7 of the globe until the liquid reaches the top of the globe portion where the liquid floats the float 9 and closes the perforation 8 in the top of the outer shell of the globe. The color of the liquid 70 will determine the color of the light rays emitted from this light unit.

When it is desired to change the color of the light rays emitted, the switch controlling the electro-magnets is raised, the 75 liquid under its own weight recedes downwardly into the bladder, thus causing the color of the light rays to again assume a white aspect.

By pressing a different switch a different 80 colored liquid is forced into the cavity in the globe and the color of the light rays are accordingly changed.

It is evident that this unit may work indefinitely by taking precautions to have the 85 globe made of materials capable of retaining the minimum amount of the liquid on the inner surfaces of the globe, or the liquid may be of such a nature as to refuse to adhere to the globe, but will entirely recede into the 90 bladder when the current is taken off the electro-magnets compressing the bladder.

It will thus be seen that I have provided a variable color lamp which will enable any 95 one to secure many colors from a single light. I desire it to be understood that I am not to be limited in the number of bladders mounted in the base portion, nor to be limited in other details, but may make such 100 changes in construction as may fall within the scope of the appended claims.

I claim:

1. A base portion, a transparent globe mounted on the base, a transparent globe of lesser dimensions than the first-named globe 105 mounted within the first mentioned globe and joined to the base of the first mentioned globe, a source of light mounted in the smaller globe, a check valve mounted in the top of the first-named globe, a bladder containing a fluid mounted below the globes and communicating with the cavity between the globes, and means for introducing the fluid contained in the bladder into the cavity, and means for withdrawing the fluid from 115 the cavity into the bladder.

2. A base containing bladders, electro-magnets for depressing said bladders, a transparent globe mounted on the base and capable of receiving a fluid, fluids of different colors in said bladders, and connections between the bladders and the fluid receiving means in the transparent globe. 120

3. In a lighting device, a base portion, a plate mounted on the base portion, a source of light mounted in the base, a transparent globe supported by the base, a globe of smaller dimensions than the first-named globe within the first-named globe, the smaller globe being concentric with the 130

first-named globe, both globes extending inwardly at their bases and being joined together and means for introducing a liquid into the space between the two globes.

- 5 4. In a device of the character set forth in claim 3, a series of bladders mounted in the base portion, electro-magnets mounted on each side of the bladders, iron members below and above said bladders, the necks of 10 said bladders extending upwardly and being connected to the cavity or space in the globe, said electro-magnets cooperating to compress the bladders and force the liquid into the cavity in the globe.
- 15 5. In a lighting device of the class described, a transparent globe, another smaller globe integral and concentric with the first-named globe, a cavity between the two globes, a plurality of flexible containers connected 20 to the said cavity, fluids of different colors contained in the flexible containers, a check valve in the apex of the first-named globe, and means associated with each of the flexible containers for forcing and withdrawing

said liquids into and from the cavity successively, at the will of the operator. 25

6. In a variable color lamp shade, an outer transparent globe having a check valve therein, an inner transparent globe spaced inwardly from the outer globe and joined to the outer globe at its base, a plurality of openings extending downwardly from the base, a source of light mounted within the globes, a base portion supporting the globes, a plurality of flexible containers located in the base portion and connected to the openings in the lower portion of the two globes, electro-magnetic means associated with the flexible containers, a liquid of any desired color in each of the flexible containers, said 30 parts cooperating to force any desired liquid into the cavity between the globes, and to withdraw said liquid from said cavity, at the will of the operator. 35

In witness that I claim the foregoing as 40 my own, I have hereunto affixed my signature this the 8th day of January 1925.

WILLIAM DOUGLAS SMITH.
